ABSTRACT: In Bendix-type starters, the stop disc has bent portions axially extending perpendicularly to its plane on the periphery of its concentric opening and is attached to the holder for the pinion by having the pinion's sleeve snugly fitted into the opening. The pinion and sleeve include the respective helical splines provided with lopped ends adapted to abut against the free edges of the bent portions on the disc. This prevents the pinion from striking against its holder ensuring that the engine is always started.

FIG. 1
PRIOR ART

FIG. 2

FIG. 3

FIG. 4

FIG. 5

STARTER FOR INTERNAL-COMBUSTION ENGINE

BACKGROUND OF THE INVENTION

This invention relates to improvements in Bendix type of starting devices for use with internal-combustion engines whereby the pinion is adapted to slide into meshing engagement with the associated ring gear for the engine by means of its own inertia.

The earlier Bendix type of starter devices referred to was disadvantageous in that upon rotating the engine by itself, the reenergization of a starting motor involved through any erroneous operation caused the pinion to push against and stick to the associated holder thereby to restrain the pinion from axially moving and therefore disable the engine from starting. Although there have been previously proposed various attempts to eliminate that disadvantage they have still exhibited objections to operation. Alternatively they have been difficult to be manufactured.

SUMMARY OF THE INVENTION

An object of the invention is to provide a new and improved starter device for use with an internal-combustion engine effective for preventing a pinion involved from sticking to the associated holder ensuring that the engine is started whenever it is necessary to do so.

The invention accomplished this object by the provision of a starting device for use with an internal-combustion engine, comprising, in combination, a shaft put in rotation upon starting the engine, a ring gear for the engine a pinion fitted onto the shaft through a helical spline sleeve and opposing to the ring gear, a buffer member for damping the movement of the pinion toward that side thereof remote from the ring gear, a holder plate disposed on the shaft between the buffer member and the pinion, and a stopper formed of a member different from the spline sleeve to prevent the pinion from abutting against the holder plate.

BRIEF DESCRIPTION OF THE DRAWING

The invention will become more readily apparent from the following detailed description taken in conjunction with the accompanying drawing in which:

FIG. 1 is a side elevational view, partly in longitudinal section of a starting device for an internal-combustion engine constructed in accordance with the principles of the prior art;

FIG. 2 is side elevational view, partly in longitudinal section of a starting device for an internal-combustion engine constructed in accordance with the principles of the invention;

FIG. 3 is a perspective view of the screw-threaded sleeve shown in FIG. 2;

FIG. 4 is a perspective sectional view of the pinion shown in FIG. 2; and

FIG. 5 is a perspective view of the screw stopper for the pinion shown in FIG. 2.

DESCRIPTION OF THE PREFERRED EMBODIMENT

Referring now to the drawing and particularly to FIG. 1 there is illustrated a starting device of the Bendix type for use with an internal-combustion engine constructed in accordance with the principles of the prior art. The arrangement illustrated comprises an output shaft 10 connectable to a starting electric motor (not shown) having a plurality of straight splines 12 disposed on the outer surface of one portion thereof, and a screw-threaded sleeve generally designated by the reference numeral 14 and having a plurality of straight splines 16 disposed on the inner peripheral surface thereof to be engaged by the straight splines 12 on the shaft 10 and a plurality of helical splines 18 disposed on the outer peripheral surface thereof. Then a pinion generally designated by the reference numeral 20 is put in spline fit with the sleeve 14 by having a plurality of helical splines 22 disposed on the inner peripheral surface thereof and engaged by the helical splines 18 on the sleeve 14. The output shaft 10 is shown in FIG. 1 as

having a helical return spring 24 disposed around the same between the sleeve 14 and a stopper 26 fixedly secured to the free end portion thereof to serve to stop the pinion 20.

As shown in FIG. 1, the pinion 20 includes an end face 5 remote from the stopper 26 and normally abutting against a holder disc 28 in the form of a thrust washer mounted on the shaft 10 and contacting a cup-shaped cover 30 also mounted on the shaft 10. An annular buffer member or cushioning means 32 made of rubber is disposed in contact relationship 10 within the cup-shaped cover 30 and supported at the free end by a support disc 34 rigidly secured on the shaft 10. FIG. 1 also shows one portion of a ring gear 36 for the engine (not shown) below the sleeve 14.

The arrangement illustrated is operated as follows: Upon 15 starting the engine (not shown), the starting motor (also not shown) is energized to acceleratedly rotate the output shaft 10 thereof. This rotational movement of the shaft 10 causes the pinion 20 to be moved from its initial starting position in the right-hand direction as viewed in FIG. 1 along the sleeve 14 due to its own inertia until it meshes with the ring gear 36. This movement to the right is accomplished by the fact that when the shaft 10 is initially rotated, the pinion 20, because of its inertia, will not immediately rotate with the shaft but instead will be axially translated along the shaft 10 towards the ring gear 36.

At the instant the pinion 20 meshes with the stationary ring gear 36, the rotational motion of the shaft 10 is imparted to the pinion 20 causing same to accordingly rotate. On the other 30 hand, as soon as the pinion 20 engages with the ring gear 36 and starts to rotate against the stationary ring gear, the latter momentarily exerts a repelling force on the pinion 20 opposing the rotational movement of the pinion. This repelling force or shock is transmitted through the helical splines 22 and 18, 35 the thrust washer 28 and the cover 30 to the resilient buffer member 32 which, due to its resilience, effectively absorbs this shock energy.

Then the ring gear 36 until it is returned back to its original 40 position as illustrated in FIG. 1 in readiness for the succeeding operation.

However the arrangement has several disadvantages which will be subsequently described.

It is now assumed that during the operation of starting the engine, the reenergization of the starting motor is erroneously 45 effected after the engine has reached the self-rotating state. Under the assumed condition the pinion 20 abuts against the ring gear 36 whereupon the pinion 20 is immediately repelled by the ring gear 36 to be moved in the left-hand direction as viewed in FIG. 1 along the sleeve 14 until it strikes against the thrust washer 28. This causes the pinion 20 to push against the washer 28 with a force sufficient to stick the pinion to the washer. Therefore the subsequent energization of the starting 50 motor causes the pinion 20 to be rotated together with the sleeve 14 without the axial movement effected resulting in the occurrence of a failure that the engine is unable to be started.

In order to avoid this failure, it has been previously considered to increase the lead angle for each of the helical splines 18 and 22 (which generally ranges from 20° to 30°) to thereby alleviate the impact of the pinion 20 on the washer 28. 55 This measure has caused the thrust force for meshing the pinion 20 with the ring gear 36 to be insufficient with the result that the pinion 20 does not always mesh with the ring gear 36. Alternatively, the pinion 20 might have a pulsating torque applied thereto by the ring gear 36 during start of the engine leading to the disengage of the pinion from the ring gear.

Also the above-mentioned disadvantage may be eliminated 60 by terminating the helical splines 18 suitably short of the side of the washer 28 without the splines running throughout the length for the purpose of restraining the pinion 20 from abutting against the washer 28. In that event the helical splines 18 can not be machined through the hobbing operation and the splines are required to be machined by reciprocating the 65 associated single cutting edge tool along the sleeve 14 as many

times as the number of the splines 18 resulting in a great reduction in productivity. Furthermore a particular single cutting edge tool relatively small in diameter is necessarily used in order satisfactorily to machine the splines in the manner as above described.

The invention contemplates to eliminate the above-mentioned disadvantages of and objections to the prior art practice.

Referring now to FIG. 2 wherein like reference numerals designate the components corresponding or similar to those shown in FIG. 1, there is illustrated a starting device for an internal-combustion engine constructed in accordance with the principles of the invention. Only the improvements made by the invention will now be described with reference to FIGS. 2 through 5.

As best shown in FIG. 3, the screw-threaded sleeve 14 is provided on the outer peripheral surface with a plurality of helical splines 18 and on the inner peripheral surface with a plurality of straight splines 16 as does the sleeve 14 shown in FIG. 1. It is, however, to be noted that those helical spline portions adjacent to the washer 28 of the sleeve 14 are lopped or trimmed off at 182 to form a plain annulus 184 between the edge of the sleeve 14 and the lopped ends 182 of the splines 18, for the purpose as will be apparent hereinafter.

The pinion 20 is similar in construction to the pinion 20 shown in FIG. 1 excepting that the helical splines 22 disposed on the inner peripheral surface thereof terminate at lopped or trimmed ends 222 formed at the end adjacent the washer 28 of the pinion 20.

As shown in FIG. 2, a position-limiting member comprising a disc-shaped screw stopper generally designated by the reference numeral 40 is rigidly secured to the exposed face of the thrust washer 28 and concentric with the shaft 10. As shown in FIG. 5, the screw stopper 40 includes a disc 402 of any suitable metallic material such as iron, and a plurality of, in this case, three bent portions or projections 404 disposed at substantially equal angular intervals on a circle having the same center as the disc 402 with the circle defining an opening 406 concentric with the disc 402. The bent portions 404 extend substantially perpendicularly to the plane of the disc 402 or axially thereof such that each bent portion merges into the plane of the disc at one end and progressively increases in height toward the other end thereof until it terminates in an axially directed edge 408 at the other end. Thus the extremity of the bent portion 404 forms a tilted or inclined edge 410.

The screw stopper as above described is preferably manufactured by punching and pressing a relatively thick piece of sheet iron.

When attached on the left-hand face as viewed in FIG. 2 to the washer 28, the screw stopper 40 has the circular opening 406 into which the plain annulus 184 is snugly fitted, the axial edges 408 abutting against the corresponding lopped ends 182 of the helical sleeve splines 18, and the tilted or inclined edges 410 abutting against the corresponding wall faces of the helical sleeve splines 18.

In operation, it is assumed that the pinion 20 has been applied with a thrust tending to move it in the left-hand direction as viewed in FIG. 2 as in the arrangement of FIG. 1. Then the lopped ends 222 of the pinion splines 22 directly abut against the axial edges 408 on the screw stopper 40 until the pinion 20 is stopped in its initial position while a gap having a distance 1 is left between the adjacent faces of the pinion 20 and the stopper 40 as shown in FIG. 2. This gap is effective for preventing the pinion 20 from striking against the washer 28, thereby to fully eliminate the failure that upon rotating the engine by itself, reenergization of the starting motor through any erroneous operation causes the pinion 20 to push against and stick to the washer 28 leading to the prevention of the axial movement of the pinion and hence the engine being disabled to be started.

If, due to the repeated impacts of the lopped ends 222 against the axial edges 408 the mechanical strength of those edges 408 come in question, then the entire screw stopper 40

may be subjected to a surface hardening treatment. Alternatively it may be suitably increased in thickness.

From the foregoing it will be appreciated that the object of the invention has been accomplished by the provision of the screw stopper serving to prevent the pinion from sticking to the holder such as the thrust washer.

While the invention has been illustrated and described in conjunction with a single preferred embodiment thereof it is to be understood that various changes in the details of construction and the arrangement and combination of parts may be resorted to without departing from the spirit and scope of the invention. For example, the washer 28 may be integral with the screw stopper 40. Alternatively the screw stopper 40 may be attached to the sleeve 14 rather than to the washer 28.

15 What we claim is:

1. A starting device engageable with a ring gear of an internal-combustion engine for starting same, comprising: a rotatable shaft, a pinion splined onto said shaft through a helically splined sleeve and having means thereon engageable with said ring gear, a buffer member for damping the movement of the pinion toward that side thereof remote from the ring gear, a holder plate disposed on said shaft between said buffer member and said pinion, and a screw stopper composed of a sheet material and attached to said holder plate effective to prevent said pinion from abutting against said holder plate.

20 2. A starting device as claimed in claim 1 wherein said stopper is disposed between said holder plate and said pinion and includes a disc, a plurality of bent portions bent substantially perpendicularly to the plane of the disc in the axial direction of the disc, and a tilted edge and an axial edge disposed on each of said bent portions, said tilted edge being capable of abutting against a helical spline disposed on said sleeve, said axial edge preventing said pinion from abutting against said holder plate.

25 3. A starting device as claimed in claim 1 wherein said stopper is disposed between said holder plate and said pinion and includes a disc, a plurality of bent portions bent substantially perpendicularly to the plane of the disc in the axial direction of the disc, and a tilted edge and an axial edge disposed on each of said bent portions and wherein said sleeve and said pinion each include a plurality of helical splines having lopped ends abutting against said axial edges of said bent portions.

30 4. In a starting device for imparting starting rotation to a driven member; a rotatable input member rotationally driven in a given direction during use of the starting device; a driving member having means thereon releasably engageable with a driven member to be rotated; means mounting said driving member on said input member for translational movement therealong between a first position wherein same is out of engagement with the driven member and a second position wherein same both releasably engages with the driven member and concurrently rotates with said input member to impart starting rotation to the driven member in response to rotation of said input member; cushioning means for cushioning the return movement of said driving member to said first position; and a position-limiting member disposed exteriorly around said input member between said cushioning means and said driving member directly engageable with said driving member during movement thereof to said first position to position same in said first position.

35 5. A starting device according to claim 4; wherein said means mounting said driving member on said input member comprises means defining helical splines on both said driving and input members in splined engagement with each other; and wherein said position-limiting member comprises an annular disc mounted on said input member and having a plurality of projections thereon projecting axially towards said driving member each of which is positioned to engage with an end portion of respective ones of said helical splines on said driving member during return movement thereof to said first position to effectively limit return movement of said driving member to said first position.

40 6. A starting device according to claim 4; wherein said means defining helical splines on both said driving and input members in splined engagement with each other; and wherein said position-limiting member comprises an annular disc mounted on said input member and having a plurality of projections thereon projecting axially towards said driving member each of which is positioned to engage with an end portion of respective ones of said helical splines on said driving member during return movement thereof to said first position to effectively limit return movement of said driving member to said first position.

45

6. A starting device according to claim 5; further including a thrust washer disposed around said input member between said cushioning means and said annular disc; and wherein said helical splines on said driving member and said projections on said annular disc are sufficiently dimensioned and configured with respect to each other to abut one another during return movement of said driving member thereby positioning same in said first position while preventing direct physical contact

between said driving member and said thrust washer.

7. A starting device according to claim 5; wherein said driving member has sufficient inertia with respect to said input member that initial rotational movement of said input member in said given direction effects translational movement therealong of said driving member from said first position to said second position.
